[57] **CLAIM**

The ornamental design for an applicator for antiperspirant, as shown and described.

DESCRIPTION

FIG. 1 is a top plan view of an applicator for antiperspirant showing my new design;

FIG. 2 is a front elevational view thereof, the rear elevational view being a mirror image;

FIG. 3 is a right side elevational view thereof, the left side elevational view being a mirror image;

FIG. 4 is a bottom plan view thereof;

FIG. 5 is a top plan view of a second embodiment of an applicator for antiperspirant;

FIG. 6 is a front elevational view thereof, the rear elevational view being a mirror image;

FIG. 7 is a right side elevational view thereof, the left side elevational view being a mirror image; and

FIG. 8 is a bottom plan view thereof.
